Attorney

UNITED STATES PATENT OFFICE.

CARL P. ASTROM, OF EAST ORANGE, NEW JERSEY, ASSIGNOR TO M. H. TREADWELL COMPANY, OF NEW YORK, N. Y., A CORPORATION OF NEW YORK.

DUMPING-CAR.

1,368,232.

Specification of Letters Patent. Patented Feb. 15, 1921.

Application filed December 1, 1919. Serial No. 341,779.

To all whom it may concern:

Be it known that I, CARL P. ASTROM, a citizen of the United States, and resident of East Orange, in the county of Essex and 5 State of New Jersey, have invented certain new and useful Improvements in Dumping-Cars, of which the following is a specification.

This invention relates to dumping cars 10 more especially for hot metal and has for its object to provide a short pouring car having simple and effective means for overcoming the body tilting during pouring and to maintain the pouring arc of the ladle 15 short and substantially constant.

According to this invention, a spring supported car body is rigidly blocked during pouring in such manner as to constitute a short pouring rigid structure adaptable for 20 standard cars without requiring special way-side dumping trunnions.

The accompanying drawing shows two forms, which can be varied without departure from the spirit and scope of the appended claims.

In the drawing,

The figure is an end elevation of a car embodying the invention, certain parts being indicated in different positions in dotted 30 lines.

5 designates a frame mounted on a suitable truck or trucks 6 traveling on the track-way 7, the truck being of standard railway type with the usual springs, one of 35 which is shown by breaking away the right hand end of the truck, journal box and axle as viewed in the figure and is designated 32.

8 designates the body provided in the present instance with opposite pouring 40 spouts 9 and 10 and with supporting and pouring trunnions 11 and 12 for the respective spouts. Trunnions 11 and 12 are each disposed laterally of the center line of the body. These pouring trunnions are supported 45 in bearings 13 and 14 provided on the frame, said bearings being of the open type to permit pouring of the body on either side, and to permit of the removal and replacement of the ladle, the ladle being shown as 50 provided with the usual lifting trunnions 15 for attachment of the crane hooks.

The dotted lines show how, when the ladle is to be poured to the right, the pouring trunnion 12 journaling in the bearing 14 55 operates as a pouring center for the ladle,

and it will be equally clear that when the ladle is tipped to the left, the pouring trunnion 11 will serve as the pouring center, giving as short a pour as desired into the runner 4. The body has the usual lugs 3 to 60 receive the crane hooks for dumping, or the body may have dumping gear and be operated by a motor.

It will be evident that when the weight of the filled body is thus shifted to one side, 65 there is a tendency to settle at the pouring side, and further that as the weight is reduced by the pouring of the metal, the springs will have a tendency to react. The preferred means consists of a stationary 70 block or wall 16 at the side of the track-way in combination with an outstanding bolster or bolsters 17 on the frame, arranged to override such stationary support, and a chock or chocks 18 bearing on the stationary 75 support, and adapted to be projected to close the gap between the stationary support and the overhanging bolster. The chock 18 may be of wedge shape, as indicated, and the under face of the bolster may be correspondingly inclined.

Ordinarily, the car will be provided with two such bolsters, one at each end and a corresponding number of chocks will be provided. Also, preferably the chocks at the 80 opposite ends of the car will be simultaneously operated, for instance, from a pivoted rock shaft 19 having rock arms 20 connected by links 21 with the respective chocks. This rock shaft is shown as operated by a hand 85 lever 22 connected with the rock shaft by an elbow lever 23, link 24 and rock arm 25. The operating lever has a weight 26 which causes it to stand in either one of the positions indicated, that is, with the chocks 90 either in projected position, or in the retracted position indicated in dotted lines.

In the operation of the apparatus, the car is run to the pouring position, the chocks at this time being retracted so that the outstanding bolsters clear the support at the side of the track. When the car is properly located the hand lever is swung to the left and the chocks are thereby brought into engagement beneath the bolsters. In this 100 relation of the parts, the weight is taken off the springs during the pouring operation so that the bearings for the pouring trunnions are supported by a fixed support at the side of the track. This results in the 105 110

pouring center being maintained substantially fixed, producing a substantially constant and short pouring arc. When the pouring is finished and the body is swung back into the position of rest, the springs react to such an extent as to cause the bolsters to clear the chocks, in which event the car may be run off without first retracting the chocks, and other cars can run on the same tracks with proper clearance.

Without this invention, the trunnions on the frame cannot be disposed far enough outward to give the desired short pour, without liability of overturning during dumping, and an important advantage is that in the figure the car automatically clears the chocks when returned to upright position after dumping.

This invention is adapted for large capacity hot metal cars, many of which hold 100 tons or more, wherein a short and constant pour is desired to avoid splashing and waste of metal, as in the runners of casting pits or machines, and where speed is necessary in order to avoid freezing in the body. With this invention the spout can go very close to the runner, and the last of the metal will discharge at practically the same spot as the first, giving what is called a short pour with good speed. The invention can be used in various other forms of cars where accurate dumping is desired of materials other than hot metal.

What I claim is:

- 35 1. In a dumping car, the combination with a body provided with a trunnion, of a frame provided with a bearing for said trunnion, and means external to said frame and positioned on the dumping side for holding said bearing to maintain the same substantially immovable during the dumping operation.
2. In a dumping car, the combination with a body provided with a trunnion, of a spring supported frame having a bearing for said trunnion, of means positioned on the dumping side for holding said frame substantially immovable during the dumping operation.
- 40 3. In a dumping car, the combination with a body provided with a trunnion, of a spring supported frame having a bearing for said trunnion, and means positioned on the dumping side for supporting said frame against swaying movement during the dumping operation.
- 45 4. In a dumping car, the combination with a body provided with a trunnion, of a frame provided with a spring supported bearing for said trunnion, and means positioned on the dumping side for holding said spring supported bearing substantially immovable during the dumping operation.
- 50 5. In a dumping car, the combination with a frame provided with bearings and

with a bolster, of a body having a trunnion journaled in said bearings, and supporting means positioned on the dumping side engageable with the bolster during dumping of the body.

6. In a dumping car, the combination with a spring supported frame and a body having a trunnion journaled in said frame, of means positioned on the dumping side for securing the frame during the dumping operation to maintain the pouring center of the body substantially fixed.

7. In a dumping car, a frame provided with a bearing and with a bolster, a body having a trunnion journaled in said bearing, and means positioned on the dumping side engageable with the bolster for supporting the frame during the dumping operation.

8. In a car dumping apparatus, the combination with a support, of a car frame having a bolster, means engageable between the support and the bolster to support the frame on the dumping side, and a dumping body mounted on the frame.

9. In combination, a track-way, a support at one side of said track-way, a car traveling on said track having a bolster overhanging the support, and a body having a trunnion journaled in said car.

10. In combination, a support, a car frame having a bolster overhanging but normally clear of the support, a body having a trunnion journaled in the frame, and a chock mounted on the support and movable to engage the overhanging bolster.

11. In combination, a support, a car frame having a bolster overhanging but normally clear of the support, a body having a trunnion journaled in the frame, a chock mounted on the support and movable to engage the bolster, and means for advancing and retracting said chock.

12. In combination, a support, a spring supported car frame having a bolster overhanging but normally clear of the support, a body having a trunnion journaled in the frame, a chock mounted on the support and adapted to be advanced into engagement with the bolster on the dumping side, said chock permitting the frame to automatically clear after dumping.

13. In combination, a support, a frame having bolsters overhanging said support but normally clear thereof, a ladle having a pouring trunnion journaled in the frame, chocks mounted on the support and means for simultaneously advancing the chocks into position beneath the bolsters on the frame, said means including a rock shaft having rock arms connected with the chocks and lever mechanism for operating said rock shaft.

14. A dumping car comprising a body mounted on trunnions outside the wheels.

for short pour, and supporting means positioned on the dumping side to prevent overturning during dumping.

15. In combination, a support, a frame 5 having a bolster overhanging but normally clear of the support, a ladle having a pouring trunnion journaled in the frame, a chock having a wedging engagement between the support and the overhanging 10 bolster and means for advancing and retarding said chock with respect to said parts.

16. In combination, a frame, wheels for supporting the same, a ladle having a pouring trunnion journaled at one side of said 15

frame and means independent of said wheels for supporting said side of the frame during the pouring operation.

17. In combination, a body having a pouring trunnion disposed laterally of the 20 center line, a frame having journals therefor, wheels for said frame, and means supplemental to said wheels for supporting the side of the frame adjacent said journals when pouring.

Signed at New York city in the county of New York and State of New York, this 26 day of November A. D. 1919.

CARL P. ASTROM.
